UNITED STATES PATENT OFFICE.

JOHN F. REED, OF OTTUMWA, IOWA.

STAPLE FORMING AND SETTING MECHANISM FOR SHOE-BUTTON-ATTACHING MACHINES.

1,279,002.

Specification of Letters Patent. Patented Sept. 17, 1918.

Application filed November 28, 1916. Serial No. 133,925.

To all whom it may concern:

Be it known that I, JOHN FRANK REED, a citizen of the United States, residing at Ottumwa, in the county of Wapello and State of Iowa, have invented new and useful Improvements in Staple Forming and Setting Mechanism for Shoe-Button-Attaching Machines, of which the following is a specification.

10 This invention relates to staple forming and setting mechanism for shoe button attaching machines, and one of its objects is to provide simple, reliable and efficient means for feeding a wire through the eye of a button and cutting off a portion thereof of a suitable length to form a staple, preliminary bending the cut wire lengths into staple form while the button is held and clamped, and then clenching the staple to fasten the button to a shoe or like article.

15 A further object of the invention is to provide a staple forming and setting mechanism of the character described which comprises a comparatively small number of 25 parts of a type not liable to get out of order, and which includes means adapted to compensate for wear of the parts and to insure proper action thereof under all conditions of service, and which means also acts to 30 allow the parts to have a yielding action to prevent injury thereto upon encountering a shoe improperly placed in position or striking any other obstruction.

35 A still further object of the invention is to provide for the positive feed of the wire under all normal conditions, while preventing any feed of the wire at all times when a button has not been fed to stapling position.

40 With these and other objects in view, the invention consists of the features of construction, combination and arrangement of parts, hereinafter fully described and claimed, reference being had to the accompanying drawings in which:

Figure 1 is a front view of the head of a shoe button attaching machine embodying my invention.

Fig. 2 is a top plan view thereof.

50 Fig. 3 is a view looking toward one side of the machine with parts in section, and showing the parts in normal position.

Fig. 4 is a sectional elevation looking toward the opposite side of the machine.

55 Fig. 5 is a vertical longitudinal section,

showing the parts in position at the completion of a staple forming action.

Fig. 6 is a similar view, showing the parts in position at the completion of the staple setting action. 60

Fig. 7 is a horizontal transverse section on line 7—7 of Fig. 5, but with the parts in position in which they appear with the machine in normal or idle position, at which time the button feed finger rests on a button in stapling position and the wire has been fed or projected through the eye thereof. 65

Fig. 8 is a similar section showing the parts in staple forming position. 70

Fig. 9 is a similar view showing the parts as illustrated in Fig. 6 in staple setting position.

Fig. 10 is a similar view illustrating the action of the parts in holding the wire feed 75 lever from action when from any cause no button has been fed to stapling position.

Fig. 11 is a detail side elevation of the button feed lever and finger, showing in full and dotted lines the normal and extended 80 throw of the mentioned parts.

Fig. 12 is a detail perspective view of the stop bar and staple forming anvil and the setting or clenching anvil.

Fig. 13 is a perspective view of the wire 85 cutting and staple forming die and the staple clenching die in assembled relation.

Fig. 14 is a similar view of the staple setting or clenching die *per se*. 90

Fig. 15 is an end view of the dies shown in Fig. 13. 95

Fig. 16 is a perspective view of the wire feed lever.

Fig. 17 is a plan view of the wire retaining dog. 95

The staple forming and setting mechanism herein disclosed is adapted for general use in connection with any suitable type of button feed mechanism, but is preferably employed in conjunction with the type of 100 button feed mechanism shown in U. S. Letters Patent 1,232,841, dated July 10, 1917.

This type of button feed mechanism embodies a button feed lever and finger having a desired coaction with the staple forming 105 and setting mechanism and which are disclosed herein, a further and more specific disclosure of the button feed mechanism being unnecessary to a full understanding of the present invention. 110

Referring to the drawings, 1 designates the head of the machine, which is suitably attached to a table or top-plate 2 which may be mounted in the usual manner upon a frame pedestal or column.

The head 1 supports the hopper 5 with which communicates and from which extends a main guide or raceway 6, which extends at a downward and forward inclination therefrom for the gravitational feed of the buttons therein to the button retaining springs or detents.

The button feeding mechanism herein disclosed also includes an outside auxiliary button guide or raceway 7 adapted to be hand fed for supplying special buttons to be applied.

Both guides or raceways are in the form of bars having upper surfaces to slidably support the heads of the buttons and longitudinal grooves to receive the eyes of the buttons, said grooves communicating at their forward ends with a single delivery groove or guideway 8 and from which the buttons are discharged for the setting action.

A single pivotally mounted feed finger 9 is provided for coöperation with both raceways for engaging and feeding the button forward to stapling position, and this finger is provided at its free end with a button receiving and engaging notch or recess 10.

In practice, suitable devices are provided for arresting the motion of the column of buttons or any single button in each guideway, so that the finger may engage and feed such button forward for the staple setting action.

The structure of these and other parts of the button feeding mechanism are described and shown simply for the purpose of making the operation of the staple forming and setting mechanism clear, the button feeding mechanism specifically forming the subject matter of my copending application hereinbefore referred to and the parts thereof of being mentioned only so far as they apply to this particular case.

The feed finger 9 is pivotally mounted upon a button feed lever 11 fulcrumed upon a supporting post 12 mounted on the head for swinging movement to move the finger forward along the button raceway.

The lever is pivotally mounted between its center and lower end, its longer arm forming a support for the feed finger and its shorter arm being provided with a pivot pin 13 which is journaled for rotation therein and provided with a transverse opening 60 to slidably receive a motion-transmitting bar 14, carrying front and rear coiled springs 15 and 16 inclosing the ends of said bar between suitable abutments and the opposite sides of the pin 13, whereby a yielding connection is afforded for advancing and

retracting the feed finger in the operation of the machine, as hereinafter described.

Pivots mounted upon the head 1 is a bell crank lever 17 having a segmental portion 18 and arms 19 and 20, to which arm 19 is pivotally connected the forward end of the rod 14, as shown at 21.

To the arm 19 is also pivotally attached the upper end of a main actuating or connection rod 22, whereby the bell crank lever 17 is attached to a suitable main operating device, such as a depressible, spring lifted or retracted foot lever (not shown), as is common with machines of this type.

To the arm 20 is connected the lifting arm 23 of a button lifting mechanism operating in the hopper 5 for the purpose of supplying buttons to the raceway 6, as set forth in said patent, for the automatic supply of buttons to such raceway on each operative movement of the machine.

The button delivery guide groove 8 is disposed in proximity to the staple setting anvil 24 which is carried by an arm 25 mounted on the head, said anvil being provided in its anvil face with a groove or recess 26 of proper form to receive the ends of the staple during the setting action.

The groove 8 is formed between a pair of parallel bars 26 and 27, which form a guideway for the staple cutting and forming member hereinafter described, and which guideway is covered at the front by a plate 28 on which the base of the head of the button 29 rests during the wire applying and staple forming action, said plate being provided with a slot 30 through which the button eye 31 projects into the delivery groove 8, the said slot and groove communicating with the space between the same and the anvil 24, in which the shoe-upper or other fabric 32 to which the button is to be attached is inserted.

The guide bar 26 is formed with a transverse opening 33 for the passage of the free end of the wire 34 across the groove 8 and through the button eye 31, which free end of the wire is limited in movement by contact with the bar 27 and is adapted to be severed from the remainder of the wire for the formation of a staple therefrom.

The wire is adapted to be fed forward from a suitable support 35 about which the wire may be wound in coil form.

The free end of the wire which is to be fed extends transversely across the forward free end of a wire feed lever 36 under a guide plate 37 and between a guide surface 38 and the tooth edge 39 of a pivoted feed dog or pawl 40, normally held in wire engaging position by a spring 41.

The lever is arranged on the outer side of the bar 26 for transverse swinging movement toward and from the same, and the teeth 39 of the dog 40 are so formed as to

- grip the wire on its forward feed movement and to slide loosely over the wire on its backward movement for the succeeding feed action.
- 5 Between the lever 36 and the bar 26 is disposed a guide member 42 similar to the guide member 37, said guide member 42 being fixed to the head 1 and carrying a spring pressed retaining dog 43 similar in 10 construction to the dog 40, the dog 43 being adapted to move forwardly with and permit of the feed motion of the wire while holding it from backward motion.

The lever 36 is pivotally mounted at 44 upon the head for swinging movement as described and has its rear end bent inwardly to form an arm 45 provided with a depending lug 46 formed with an opening 47 to slidably receive a rod 48, which is pivotally attached at its forward end to the body of the bell crank lever 17, as indicated at 49.

Surrounding said rod 48 are coiled springs 50 and 51, the spring 50 being disposed between the lug 46 and an abutment upon the 25 pivoted end of the rod, and the spring 51 being disposed between the lug and an abutment 52 at the rear end of the rod.

When the rod 22 is drawn downward the rod 14 is pulled downward and forward 30 and tensions the spring 16, thus exerting a pull upon the lever 11 to swing the finger 9 backward on its retracting motion.

On the downward movement of the rod 22 the segmental portion 18 of the bell crank 35 17 is moved forwardly, thereby compressing the spring 51 for forcing pressure against the lug 46 to swing the wire feed lever outwardly on its retractive motion.

When the rod 22 moves upwardly or is 40 retracted upon the release of the foot lever by the action of the retracting spring of said lever, the springs 15 and 50 act to project the button feed finger and wire feed lever on their feed motions.

45 The springs 15, 16, 50 and 51 provide, in connection with rods 14 and 48, yielding pressure, lost motion connections between the bell crank lever and the button feed and the wire feed levers, whereby any irregularities of motion due to wear are compensated for and taken up, and whereby a full operating motion of the bell crank lever is permitted to take place and the button and wire feed levers permitted to have certain compensating actions at times when no button has been fed forward to stapling position by the button feed finger from a raceway and no wire is required to be fed up as hereinafter 55 fully described.

60 The staple forming and setting mechanism proper comprises a staple cutting and forming member 53 and a staple driving or setting die 54, together with certain operating parts, as hereinafter specified.

65 The die or ram 53 comprises an oblong

rectangular block mounted for reciprocation in the guideway formed between the bars 26 and 27, while the die or ram 54 also comprises a block of oblong rectangular form and of less width but greater length 70 than the die 53.

The die 53 is bifurcated at its forward end to form a vertical slot 55 and is provided in its upper surface with a longitudinally extending groove 56 communicating 75 at its forward end with said slot, and in which the die 54 is reciprocably mounted, said die 53 being provided in the side walls of the slot and groove with staple receiving 80 and guide grooves 57, and the die 54 having longitudinally extending ribs 58 movable in said grooves 57.

The forward end of the die member 53 is provided with straight forming surfaces 59 having transverse receiving grooves 60 and 85 is also formed with beveled abutment surfaces 61 below said surfaces 59, while the die member 54 is provided in the forward portion of its upper face with a longitudinally extending groove 62 to receive and 90 permit feed motion of the eye of the button, and its forward end is formed with straight abutment surfaces 63 provided with transverse grooves 64, and with beveled abutment surfaces 65, the surface 63 and 65 95 of the staple driving and setting die being adapted to register with the surfaces 59 and 61 of the die 53 when said staple driving and setting die is fully moved forward.

The inner edge portions of 63 are cut away 100 at an oblique angle, as shown at 66, and provided with grooves which constitute inward continuations of the groove 64, to adapt said surfaces to have a specific action in setting the staple.

In the lower face of the die 54 are formed recesses 67 and 68 adapted for engagement with teeth 69 and 70 on the segmental portion of the bell crank lever 17, which acts as a gear element, and whereby the die member 54 is adapted to be moved forwardly in two stages or steps.

Guide rods 71 are arranged on opposite sides of the die member 54 and are slidably longitudinally in sockets 72 in the die member 53, and coiled springs 73 are disposed and tensioned on said rods between abutments thereon and the rear end of the die member 53, the die member 54 is provided with a shoulder 75 which is adapted to engage a cross pin 76 on the die member 53 to hold said die members from relative displacement, and said surface 75 also acts upon the cross pin 76 to limit the rear movement of the member 54.

The die member 54, and the die member 53, are adapted to be moved forwardly together by engagement of the gear tooth 69, with the rear end of the die member 53, and the gear tooth 70 with the notch 68, or from 130

the position shown in Fig. 3 to that shown in Fig. 5, at which time the tooth 69 has moved from engagement with the rear end of the die member 53, the die member 53 being carried forward during its further forward movement by the springs 73.

The die member 54 is adapted to be moved forward independently of the die member 53 during the button setting action or after the 10 die member 53 has completed its forward movement, the springs 73 being further tensioned and compressed against the rear end of the said die member 53 as the die member 54 is carried forward to complete the setting 15 action.

The action of the springs 73 affords variable forward movement to the die member 53, also holds fabrics of varying thicknesses during the setting action, which are interposed between the forward end of the die member 53 and the face of the clenching anvil 24, such operation of the die members and springs occurring on each working stroke of the bell crank lever 17.

25 A button having been fed forward in the guideway by the button feed finger to stapling position, as shown in Fig. 3, it will be understood that upon the depression of the operating treadle the arm 19 of the bell 30 crank lever will be drawn downward, thus transmitting a backward retractive motion to the button feed lever and finger, as shown in Fig. 6.

After the die member 53 has been retracted 35 beyond the passage 33, the wire feed lever 36 feeds the wire through the passage-way 38 and across the guideway between the bars 26 and 27 in position to come between the ends of the dies and a bending anvil 77 40 upon the upper inclined end abutment surface 78 of a vertically movable anvil and stop-bar 79 normally held projected upward in the path of the die members and between the same and the anvil 24 by expansive action 45 of a spring 80.

The anvil 77 of this bar has its anvil surface formed with a straight face 81 and lateral oblique faces 82 for co-operation with the surfaces of the reciprocating die 53.

50 In the preliminary forward movement of the reciprocating dies the corner edge of the adjacent surface 59 of the die 53 cuts off the projected portion of the wire from the body of the wire, which projected portion 55 of the wire has been threaded or passed through the eye of the button held in stapling position by the button feed finger resting thereon and the eye of the button resting against the surface 81 of the anvil 77, 60 and then as the die member 53 continues its forward movement the ends of the wire are engaged and held in the grooves 60 and forced forward by the die 53 against the anvil 77, by which the wire is bent into 65 staple form and received in the grooves 57

of the die 53 by the anvil 77 which enters the slot 55 of said die 53.

At this stage the die 53 moves forward on its second step and its sloping surface 61 engages the sloping surface 78 of the block 79 70 and forces said block downward, as shown in Fig. 6, out of the path of the die member 53 and 54, at which time the forward end of the die 54 will have come into position to engage the formed staple, as shown in 75 Fig. 8.

The fabric 32 having been previously placed in position for the setting action, the continued forward movement of the dies 53 and 54 will result in the end of the die 53 80 being brought into contact with the fabric so as to clamp the same against the anvil 24, the die 54 forcing the ends of the staple through the fabric and its surfaces co-operating with the groove 26 in the anvil 24 to 85 bend the ends of the staple inwardly and clench the same against the fabric while the forming surfaces of the die 54 contract the bight of the staple about the eye of the button, as shown in Fig. 9, whereby the button 90 will be set or fastened to the fabric.

The operating treadle then being released, the retracting springs will return the parts to normal position and the finger 9 will again move downwardly and forwardly, its 95 notched end engaging and feeding a button forward to stapling position against the surface 81 of the block 79 which has again been moved by its spring 80 upward into the path of the dies.

100 It is desirable to provide some means for preventing the wire feed motion of the wire feed lever when through any cause a button has not been fed forward to stapling position, and to do this without adding to 105 the complexity of the machine.

To this end the button feed lever and finger are permitted to have an abnormal forward movement when no button has been fed to stapling position by the button feed 110 finger, as indicated in full and dotted lines in Fig. 11, showing in full lines the feed movement when a button is in position and in dotted lines an extended range of movement when no button is in stapling position, or in position to arrest the forward motion of the feed finger and lever.

115 This extended forward movement of the feed lever and finger is permitted by the range of movement allowed by the spring 120 15, which, when the finger engages a button, is compressed to a slightly greater degree than when the finger is permitted to have an abnormal travel, thus avoiding liability of injury to or derangement of the 125 parts under such conditions.

When the lever 11 moves forwardly to its normal degree, the arm 82' is permitted to pass said lever 11 thus permitting the wire feed lever 36 to fully feed the wire forward, 130

- but when the lever 11 moves forward to an abnormal degree, said lever 11 comes into position to be engaged by the surface 84 of the arm 82', so that it acts as a stop to prevent the lever 36 from a forward feeding movement of the wire into the guideway between the bars 26 and 27, thus preventing the formation of a staple when no button is in stapling position.
- 10 The stop motion of the lever 36 is permitted by reason of the elastic lost motion connection formed by the rod 48 and spring 50, which spring, when the full travel of the lever 36 is arrested, will be compressed to a slightly greater degree than when the lever has its full movement, so that the bell crank and stapling dies are permitted to have a full range of travel without obstruction or the imposition of strains thereon.
- 15 It will be observed that the elastic lost motion connections between the actuating bell crank and the button and wire feed means also insure the compensating action of the character described in a smooth and easy manner, and without jar or jerk even when variations of motion occur due to wear of the working parts.
- 20 By the present structure it will be evident that the button feed lever serves directly the function of a stop for limiting the motion of the wire feed lever under the condition mentioned without the addition of part or parts, to which extent it forms a part of the staple forming and setting mechanism.
- 25 It will be evident, of course, that my improved staple forming and setting mechanism may be employed for general purposes in fastening buttons and the like to various kinds of fabric and that it may be employed in conjunction with button machines in which the buttons are fed either automatically or by hand to the machine, hence the invention is not limited to its use in connection with any particular type of feed mechanism, except as set forth in the claims.
- 30 It will, of course, be understood that while the structure shown is proper, any equivalent construction, falling within the scope of the appended claims, may be employed without departing from the spirit or sacrificing any of the advantages of the invention.
- 35 I claim:—
1. A button attaching machine comprising a button feeding lever having a normal movement when a button is in position to be fed and an extending movement when a button is not in position to be fed, a wire feeding lever having a projection thereon for engaging the button feeding lever when the same is in abnormal position to prevent the wire feeding action, staple forming and setting means, and actuating means for the parts.
- 40 2. A button attaching machine comprising a vertically arranged button feeding lever, means for rocking the same, a button engaging member carried by said lever, a horizontally arranged wire feeding lever, means for rocking the same horizontally, a right angular projection carried by said wire feeding lever and adapted to contact with the button feeding lever when the button is not in position to prevent movement of said wire feeding lever, staple forming and setting means, and operating means for actuating the parts.
- 45 3. In a button attaching machine, the combination of a staple setting die, a wire feeder, a button feeder operative in the absence of a button to arrest the motion of the wire feeder, a staple forming die movable toward and from the setting anvil, a staple forming anvil movable into and out of the path of said forming die, a staple setting die slidably connected with said forming die, motion transmitting springs connecting said dies, and a bell crank lever in gear with the setting die for imparting motion thereto, and sliding spring controlled lost motion connections between said bell crank lever and the wire and button feeders.

In testimony whereof I affix my signature.

JOHN F. REED.
